UNITED STATES PATENT OFFICE.

JOHN GUSSETT, OF BRIDGEPORT, CONNECTICUT.

COLLAR FASTENER.

1,427,531.

Specification of Letters Patent. Patented Aug. 29, 1922.

Application filed November 5, 1921. Serial No. 512,999.

To all whom it may concern:

Be it known that JOHN GUSSETT, a citizen of the United States, and resident of Bridgeport, in the county of Fairfield and State 5 of Connecticut, has invented certain new and useful Improvements in Collar Fasteners, of which the following is a specification.

This invention relates to a novel and improved collar fastener and the object of the 10 invention is to provide a collar fastener for securing the rear part of a collar to a shirt band which will be simple and inexpensive and more suited to its purpose than any heretofore known.

15 With the above and other objects in view, the invention comprises the construction, arrangement and combination of parts as now to be fully described and as hereinafter to be specifically claimed.

20 In the accompanying drawing forming a part of this specification,

Fig. 1 is an elevational view illustrating the rear of a shirt band having the device of the invention applied thereto;

25 Fig. 2 is a view in vertical section of a collar and neck band, showing my collar fastener as in use;

Fig. 3 is an elevational view of the fastener detached; and

30 Fig. 4 is a top plan view of the fastener.

With reference to the drawing, 10 denotes a shirt band, 11 a collar, and 12 denotes generally the fastener consisting of a longitudinally curved body 13 merging at 14 into 35 a tongue 15 extending transversely of the body and being approximately parallel therewith. The free end of the tongue may be bent outwardly so that the fastener can be more easily inserted in the button holes 40 of a shirt band and collar.

It is to be noted that that edge of the longitudinally curved body 13 which is to become the top when the fastener is in use, denoted by 16, lies in a single plane, and that 45 the portion of said edge upon opposite sides of the tongue 15 are in direct alignment. The location 14 at which the body merges into the tongue defines a smooth curve positioned closely adjacent the upper edge 16 50 of the body.

As is usual in the case of collar fasteners of the present type, the body portion 13 is inserted between the folds of a neck band

and the tongue is inserted first through the button hole 17 of the outer fold of said band 55 and then through the rear button hole 18 of a collar, the flat top edge 16 of the body lying closely adjacent the button hole 17 and the smoothly curved portion 14 of the fastener extending through the button holes 60 17 and 18.

A fastener of the construction shown and described will be fixed in the shirt band against accidental displacement. It cannot be drawn upwardly when in use, because the 65 top edge of the longitudinally curved body 13, lying closely adjacent the button hole 17, presents itself against the material of the outer fold of the shirt band when upward pressure is exerted against the fastener. 70 The fastener cannot, obviously, be drawn downwardly unless intentionally removed from the shirt band.

By the provision of a body such as described and the arrangement of the tongue 75 in the manner set forth, a very simple and comfortable fastener requiring but a minimum amount of space, allowing the collar to snugly fit the shirt band and necessitating but a thin strip of material in the lower portions of the folds of the band, is obtained. 80

Having thus fully described the invention, what I claim as new and desire to secure by Letters Patent is:

A collar fastener comprising a longitudinally curved body having a top edge which in its entirety lies in a single plane and merges on a smooth curve into a tongue, said tongue being parallel with and arranged transversely of said body, said top edge of 90 said body being constructed to lie closely adjacent to the button hole of a shirt band, the material of said fastener constituting said smooth curve lying in said button hole, and the material of the longitudinally 95 curved body lying in its entirety within said shirt band, whereby when said body is between the folds of a shirt band and said tongue is inserted through said button hole, upward pressure against said tongue 100 will be resisted by the engagement of said top edge against one of said folds.

Signed at Bridgeport, in the county of Fairfield and State of Connecticut, this 2nd day of November, A. D. 1921.

JOHN GUSSETT.
